UNITED STATES PATENT OFFICE.

FRED WOOD, OF TAUNTON, MASSACHUSETTS.

ROVING-CREEL.

1,324,710.

Specification of Letters Patent.

Patented Dec. 9, 1919.

Application filed August 13, 1918. Serial No. 249,702.

To all whom it may concern:

Be it known that I, FRED Wood, a citizen of the United States, residing at Taunton, in the county of Bristol and State of Massachusetts, have invented certain new and useful Improvements in Roving-Creels; and I do hereby declare the following to be a full, clear, and exact description of the invention, such as will enable others skilled in the art 10 to which it appertains to make and use the same.

My invention relates to improvements in roving creels having means for expeditiously and conveniently collecting the speeder bobbins therefor.

In the roving creels now in use, the empty speeder or roving bobbins are placed upon the top of the creel to be removed by an attendant. In removing the empty bobbins, 20 the attendant frequently leans against or drops some of the empty bobbins on the thread or yarn in the creel with the result that the thread or yarn is broken. In addition to frequently breaking the thread or 25 yarn in the creel, the attendant interferes to an appreciable extent with the work of the operator of the creel and thus retards the production of the machine.

An important object of this invention is to 30 provide a chute for the creel, adapted to convey the empty roving bobbins to one end of the creel, at which point they are dumped into a suitable receptacle.

A further object of the invention is to 35 provide a collecting apparatus for the empty bobbins which may be applied to the creels now in use or may be manufactured therewith.

Other objects and advantages of the invention will be apparent during the course 40 of the following description.

In the accompanying drawings, forming a part of this specification and in which like numerals are employed to designate like 45 parts throughout the same,

Figure 1 is a fragmentary perspective of a roving creel having my improved bobbin collecting device applied thereto,

Fig. 2 is a transverse section taken on line 50 2—2 of Fig. 1,

Fig. 3 is a central vertical section through a receptacle for receiving the empty bobbins, the same being shown applied to one end of the creel,

55 Fig. 4 is a vertical transverse section through the receptacle for receiving the

empty bobbins, the view being taken at right angles to the view shown in Fig. 3,

Fig. 5 is a perspective of the receptacle for receiving the empty bobbins, and

Fig. 6 is a fragmentary vertical transverse section taken through the receptacle for receiving the bobbins.

In the drawings wherein for the purpose of illustration is shown the preferred embodiment of my invention, the numeral 10 generically designates a roving creel adapted to receive a number of speeder or roving bobbins. The top 11 of the creel ordinarily serves to receive the empty bobbins prior to 70 being removed by an attendant. The top 11 also serves to receive the filled bobbins.

Vertical longitudinally extending sides 12 are provided for the top 11 of the creel.

As clearly illustrated in Figs. 1 and 2, the 75 side walls 12 on opposite sides of the top 11 are adapted to coat with horizontal and vertical longitudinally extending strips 13 and 14, respectively, thus forming chutes generically designated by the numeral 15. 80

The outer vertical side walls 14 extend above the inner walls 12 of the chutes. The empty bobbins are adapted to be placed lengthwise in the chutes. The interior surfaces of the chutes 15 are relatively smooth, thus reducing to a minimum, the friction between the empty bobbins and the chutes. Attached to 85 one end of the creel and communicating with the bobbins is a receptacle 16. Brackets 17 having U-shaped arms 18 serve to secure 90 the receptacle 16 to the end of the creel. The inner side 19 of the receptacle 16 is provided along its upper edge with semi-circular recesses 19' registering with the chutes 15 to permit of the free passage of the empty 95 bobbins into the receptacle. The rear side of the receptacle 16 is cut away as shown at 20 to provide for the housing 21 of the propelling mechanism of the creel. The outer side of the receptacle 16 is provided with 100 a door 22 secured thereto by hinges 23. A lock 24 serves to retain the door closed when desired.

The function of the door 22 is to permit of the discharge of the empty bobbins within the receptacle into a suitable conveyance which may be placed beneath the receptacle.

In the use of my improved bobbin collecting device, a number of empty bobbins are placed within the chutes 15, and by a slight 110 movement of the hand the empty bobbins are passed into the receptacles 16. An attend-

ant may remove the empty bobbins from the receptacle 17 by placing the same in a suitable conveyance.

While I have shown and described the preferred embodiment of my invention, it is understood that I may make such minor changes in arrangement and construction of parts, as will remain within the spirit of the invention, and scope of the appended 10 claims.

Having thus described my invention, what I claim is:—

1. The combination with a creel having a horizontal top and vertical side walls secured thereto, of horizontal and vertical longitudinally extending strips secured to said vertical sides and adapted to coat therewith in forming bobbin conveying chutes, and a bobbin receiving receptacle arranged at one 20 end of the chutes.
2. The combination with a creel having a top and vertical side walls therefor, of horizontal and vertical longitudinally extending strips attached to said side walls and 25 adapted to coat therewith in forming a bobbin conveying chute, said vertical longi-

tudinally extending strips extending above the plane of the side walls of the top of said creel, and a bobbin receiving receptacle 30 arranged at one end of the chutes.

3. The combination with a creel having a horizontal top and vertical side walls for said top, of horizontal and vertical longitudinally extending strips secured to said side 35 walls of the top and coacting therewith in forming bobbin conveying chutes, and a receptacle arranged at one end of the chutes and adapted to receive the bobbins, said receptacle having recesses in its upper edge 40 adapted to register with said chutes.

4. The combination with a creel having a horizontal top and vertical side walls secured thereto, and horizontal and vertical longitudinally extending strips secured to 45 said vertical sides for forming chutes.

In testimony whereof I affix my signature in presence of two witnesses.

FRED WOOD.
